UNITED STATES PATENT OFFICE.

AUGUST GRASKE, OF OMAHA, NEBRASKA.

GRIP FOR BOW-TIES.

1,343,623.

Specification of Letters Patent. Patented June 15, 1920.

Application filed January 27, 1920. Serial No. 354,411.

To all whom it may concern:

Be it known that I, AUGUST GRASKE, a citizen of the United States, residing at Omaha, in the county of Douglas and State 5 of Nebraska, have invented certain new and useful Improvements in Grips for Bow-Ties, of which the following is a specification.

This invention relates to bow tie grips of that general type which is sewed to the back 10 of the tie and holds the latter in place by gripping the two front edges of a turn-down collar. Numerous holders or grips for bow ties of this general character have been devised, but so far as my observation goes, 15 none of them has proved entirely satisfactory and reliable in use. Unless the grip or fastener clamps the edge of the collar very securely, the tie is apt to slip down and expose the collar button and sometimes fall off 20 altogether. Furthermore, where the grip or clamp is made as a continuous piece spanning the space between the front edges of the collar it does not always conform to the angle of the meeting ends of the collar, and, 25 when applied, produces an objectionable bulging of the front ends and sides of the collar.

With these and other defects of the known 30 bow tie fasteners in mind, I have devised the bow tie grip of my present invention, the principal object of which is to provide a device that shall be free from the above-named faults, shall be simple and economical to manufacture, shall hold the tie 35 securely in place on the collar, and will readily conform to the angle of the meeting ends of the collar.

Still other objects and advantages of the 40 invention will be apparent to those skilled in the art as the invention becomes better understood by reference to the following description, taken in connection with the accompanying drawing wherein I have shown one practical and approved embodiment of 45 the invention, and in which—

Figure 1 is a front elevation of a collar and bow tie, the latter being shown in dotted lines, showing my improved tie grip applied thereto;

Fig. 2 is a horizontal section, taken on the line 2—2 of Fig. 1;

Fig. 3 is an elevation of the grip or fastener as viewed from the back of the tie; and

Fig. 4 is a top edge view of one of the 55 clamps.

Referring to the drawing, 5 designates

each of the two end portions of the front fold of a turn-down collar, and 6 designates the wings and 7 the central cross-band of a ready-made bow tie. The tie grip or fastener, which is secured to the back of the tie so as to be concealed when in use as usual with this class of devices, comprises a pair of oppositely extending clamps each designated as a whole by A and a connecting link 60 B. Each of these clamps A is cut and pressed to shape from a blank of resilient sheet metal, and comprises a base strip 8, the inner end of which is folded over to form a hinge-member 9, and a narrow tongue 10 65 that is formed as an integral extension of the hinge-member 9. The base strip 8 is preferably formed with a longitudinal slot 11 of slightly greater width than the tongue 10; and the central portions of the base strip 70 8 and tongue 10 are bent or bowed toward each other so that the central portion of the tongue, when the device is off the collar, normally lies in the slot 11, as indicated in Fig. 4. The outer end portions of the strip and 75 tongue diverge sufficiently to enable the outer end of the clamp to be readily passed over the end of the collar fold 5. In doing this, the tongue 10 is sprung outwardly, the collar fold passing between the base strip 80 and tongue and being tightly gripped or clamped thereby. This gripping or clamping action is much enhanced by providing the slot 11 in the base strip 8 in which the central bowed portion of the tongue 10 lies 80 in the normal set position of the metal, since the amount of spread of the clamping members 8 and 10, when the collar fold is forced between them, is greater than where the clamping members merely lie in surface contact, with a consequent increase in the 85 strength of the gripping or clamping action.

The two clamps are connected by the hinge link B, the two opposite sides 12 of which lie within the hinge-members 9 of the clamps, 100 the other two sides 13 of the hinge link being attached to the cross band 7 of the tie by suitable stitching or otherwise. To provide adequate friction joints in the hinges, small tongues 14 are preferably cut and bent down 105 from the metal of the hinge members 9 into frictional engagement with the sides 12 of the hinge link B. Holes 15 in the ends of the base strips 8 facilitate attachment of the latter to the back of the tie by loops of thread 110 in an obvious manner.

The manner in which the stated objects

of the invention are attained will be readily perceived from the foregoing description. The clamping members 8 and 10, constructed as described, secure a sufficiently strong grip 5 on the collar to prevent all danger of the tie slipping down and off the collar by accident; and the frictionally jointed character of the grip enables it to readily conform to the angle at which the collar folds 5 meet, 10 so that there is no tendency on the part of the grip to bulge or otherwise distort the folds of the collar from the positions in which they naturally lie on the neck of the wearer.

15 Variations in structural details from the specific form of the device shown and described may manifestly be made without departing from the principle of the invention or sacrificing any of the advantages 20 thereof. Hence, I reserve all such variations and modifications as fall within the spirit and purview of the appended claims.

I claim—

1. A bow tie grip of the character described, comprising a pair of clamps adapted 25 to grip the front edges of a collar, said clamps being hinged together at their inner ends.

2. A bow tie grip of the character described, comprising a pair of metal clamps 30 adapted to grip the front edges of a collar, and a connecting link to which the inner ends of said clamps are flexibly jointed.

3. A bow tie grip of the character described, comprising a pair of clamps adapted 35 to grip the front edges of a collar, each of said clamps comprising a pair of integral elastic gripping members formed with divergent outer ends to facilitate the passage 40 of the clamp over the fold of a collar, and a connecting link to which the inner ends of said clamps are flexibly jointed.

4. A bow tie grip of the character described, comprising a pair of clamps adapted to grip the front edges of a collar, each of 45 said clamps comprising a base strip adapted to be attached to the back of the tie and an integral elastic tongue folded over and lying in front of said base strip, said base strip and tongue being formed with divergent outer ends to facilitate the passage 50 of the clamp over the fold of a collar, and a connecting link to which the inner ends of said clamps are flexibly jointed.

5. A box tie grip of the character described, comprising a pair of clamps adapted to grip the front edges of a collar, each of said clamps comprising a longitudinally slotted base strip adapted for attachment to the back of the tie and an integral narrow 60 elastic tongue folded over and lying opposite and partly within the slot of said base strip, said base strip and tongue having divergent outer ends to facilitate the passage 65 of the clamp over the fold of a collar, and a connecting link to which the inner ends of said clamps are flexibly jointed.

6. A bow tie grip of the character described, comprising a central link adapted 70 for attachment to the back of the tie, and a pair of clamps hinged to the opposite sides of said link, each of said clamps comprising a longitudinally slotted base strip adapted for attachment to the back of the tie and a narrow elastic curved tongue constituting a folded extension of the inner end 75 of said base strip and lying opposite and partly within the slot of the latter, said base strip and tongue having divergent outer ends to facilitate the passage of the clamp 80 over the fold of a collar, and said base strips further having inwardly bent lugs frictionally engaged with the sides of said link.

AUGUST GRASKE.
